UNITED STATES PATENT OFFICE.

CHARLES I. SIGNER, OF OLYMPIA, WASHINGTON.

ANTISKID-CABLE END FASTENER.

Application filed January 19, 1924. Serial No. 687,176.

To all whom it may concern:

Be it known that CHARLES I. SIGNER, a citizen of the United States, residing at Olympia, in the county of Thurston and State of Washington, has invented certain new and useful Improvements in Antiskid-Cable End Fasteners, of which the following is a specification.

This invention is in the way of an anti-skid cable for automobiles, and the object is to provide a device of this nature having special forms of main and cross cable fasteners, whereby the main cables may be quickly adjusted or tightened, and any required number of cross cables may be mounted on the main cables.

In the drawing—

Figure 1 is a plan view of a sheet metal blank designed to form one of the main cable end fasteners;

Figure 2 is a detail of one of the chuck or clutch rollers;

Figure 3 is a detail of one of the rivets for holding the sides of the fasteners together;

Figure 4 is a side view of one of the main cable fasteners folded from the blank shown in Figure 1 and with the clutch rollers mounted in place therein and the ends of the main cable passed therethrough;

Figure 5 is an edge view of the assembly shown in Figure 4;

Figure 6 is a plan view of a sheet metal blank for one of the cross cable fasteners;

Figure 7 is a side view of one of the cross cable fasteners folded from the blank of Figure 6, showing the main cable passed therethrough, and the ends of a cross cable secured therein.

Figures 8 and 9 are edge views of the assembly shown in Figure 7.

In carrying out the invention, wire cables 1 are employed as main cables, one being intended for each side of the automobile wheel (not shown) and to be positioned in usual manner. Main cable end fasteners 2 are provided, the same being formed from sheet metal blanks 3 having obliquely directed roller slots 4 cut therein and enlarged at their inner ends, as shown at 5. These blanks are also formed with rivet holes 6, a cable slot 7 and cable holes 8. The blanks are folded upon the medial line to the form shown in Figures 4 and 5. Clutch rollers

9 are then seated in the slots 4, having their ends journaled in these slots, and the fasteners are then riveted together by rivets 10. One end of the wire cable 1 is passed through the cable holes 8 of the folded ends of the fastener, and this end is permanently locked therein by enlarging the end as shown at 11. The other end 12 is passed longitudinally through the fastener, and out through the cable slot 7 at one side. This device enables the ready adjustment of the cable and locking same by means of the clutch rollers 9. Cross cable fasteners 13 are provided, the same being likewise formed of sheet metal blanks 14 with rivet holes 15 cut therein. The cross cables 16 are positioned therein, and the sides and ends are then folded over to the form shown in Figure 7, and secured by rivets 17. This construction leaves loops 18 at the ends of the fasteners through which the main cables 1 are slidably passed. As many cross cables may be employed as desired. The operation and use of the device is apparent.

While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

I claim:

An anti-skid cable end fastener formed of an elongated, rectangular sheet metal blank 90 having a medial cable slot at one end, cable holes at the sides of the cable slot, and obliquely directed roller slots with enlarged inner ends at each side of the blank; the blank being folded upon its medial line to form a cable way, and the free corners of the blank carrying the cable holes being bent inwardly and overlapped with the cable holes registering with each other to form a cable end locking means, a portion of the cable slot 95 being left open as a cable run way; and clutch rollers operatively mounted in the fastener with their ends journaled through the said roller slots.

In testimony whereof I affix my signature.

CHARLES I. SIGNER.
